Inventor

UNITED STATES PATENT OFFICE

JOHN KOVATS, OF BRIDGEPORT, CONNECTICUT, ASSIGNOR TO THE LEG-O-MATIC COMPANY, OF BRIDGEPORT, CONNECTICUT, A CORPORATION OF CONNECTICUT

FOLDING TABLE

Application filed May 31, 1930. Serial No. 458,012.

This invention relates to a table, particularly to a means for mounting the supporting legs of the table, and has for an object to provide means for so connecting the supporting legs to the table that they may all be folded against the under side of the table, and are connected by mechanism so that the swinging of any one leg to or from the extended or supporting position will impart a similar and simultaneous movement to each of the other legs.

It is also an object of this invention to provide a construction in which there is a single manually releasable locking means which is so connected to the leg connecting mechanism that the legs will all be automatically locked when they are swung to the supporting position, and the release of the locking means will permit any one leg to be swung to folded position, and all the other legs will simultaneously be swung to folded position by the connecting mechanism.

It is another object of the invention to provide a construction in which, although all the legs may be swung to or from the extended or folded position by swinging any individual leg on its pivot, still the legs are rigidly held in the supporting position to provide a rigid support for the table.

It is still another object of the invention to provide a construction of this character in which practically the entire structure including the linked members interconnecting operating train of mechanism, may be stamped from sheet metal and may be manufactured and assembled at relatively low cost.

With the foregoing and other objects in view, the invention consists in certain novel features of construction, combinations and arrangements of parts as will be more fully disclosed in connection with the accompanying drawing.

In this drawing,

Fig. 1 is a bottom plan view of a table showing the legs folded against the under side thereof.

Fig. 2 is an enlarged view of one edge of the under side of the table with the legs in extended or supporting position, and is on line 2-2 of Fig. 3.

Fig. 3 is a section looking in the direction of the arrows on the line 3-3 of Fig. 2.

Fig. 4 is a detail section on line 4-4 of Fig. 3.

Fig. 5 is a detail section on line 5-5 of Fig. 3.

Fig. 6 is a detail section on line 6-6 of Fig. 3.

This device is adapted for tables of various types, but is especially intended for use on what are commonly known as card tables in which the legs are foldable against the under side of the table top, so that the table may be folded into a small space and put away into a closet or other suitable space when not in use, and the device is, therefore, shown in the drawing as applied to this type of table. The table top is shown at 12 which, of course, may be of any suitable material and may be finished on the top or covered with any suitable cover as is found desirable. Secured to the under side of this type of the table and extending about the periphery thereof are usually mounted wooden bars 13 which strengthen and stiffen the table top and assist in preventing warping. The table shown is a substantially square or rectangular table and is, therefore, provided with a supporting leg 14 at each corner. These legs are each pivoted to the table so as to fold or swing against the under side thereof and they are all mounted in the same manner. They thus each swing in the same direction in relation to the periphery of the table from their individual corners and lie substantially parallel with the bar or flange 13 when they are folded against the under side of the table top.

As the means for mounting each is the same as that for mounting each of the other legs one set of dies may be used for making all the mountings and they are, therefore, each interchangeable, and I will describe but one of them.

The legs 14 are substantially square in cross section, but, of course, may be of any shape desired. The upper end of each leg is pivoted at 15 in a bracket 16 which is secured at each corner to the under side of the table by bolts 17. Pivoted to each leg as at 18 is a link or brace 19 which serves to brace

the leg when in extended or supporting position and also serves as a factor in the transmission of pivoting movement from one leg to the other leg by the train of mechanism 5 about to be described. Affixed to each side of the table, and more particularly to the inner side of bar 13, by means of bolts 20 and 21 is a guideway 22 which is so shaped as to have a plurality of slots 23 therein spaced 10 from the bar 13 so as to provide clearance for the heads of the studs 24, 25 and 26. Slidably guided and retained by these studs is the flat strap 27 having ears 28 and 29 projecting at right angles thereto along the 15 side near each end thereof.

Stud 26 also serves as a pivoting pin for pivoting brace or link 19 to the nearer end of strap 27, so that reciprocatory movement of strap 27 will be translated into pivotal movement of legs 14 and vice versa. Affixed to the table diagonally of each corner is another guideway 30, one end of which is held to a bar 13 by a bolt 31 and the other end to the adjacent bar 13 by the same bolt 21 that holds one end of guideway 22. In the guideway 30 is a slot 30' spaced from the table to provide clearance for the head of a pivoting stud 32 which serves to connect and guide the movements of a pair of links 33 the other 20 ends of links 33 being pivotally connected to ears 28 and 29 at 28' and 29' respectively.

In order to releasably lock the train against movement when the legs are in supporting position, a spring catch or lock 34 is fastened to one of the bars 13 at 35 and has a tongue 36 in position to abut the further end of one of the straps 27 when the legs are extended to supporting position. A finger catch or lip 37 is bent away from the end 40 of latch 34 and serves to raise tongue 36 out of contact with strap 27 that it may slide by it.

The operation of the table is quite simple. When the legs are folded in the position 45 shown in Fig. 1, it is only necessary for the operator to grasp any one leg and pivot it to the extended or supporting position. The pivoting of this leg will operate, by means of brace 19, to move the strap 27 to which the 50 brace is pivoted, which in turn will move the links 33 and hence all the other straps 27 and thereby simultaneously pivot all the other legs to extended position. When the legs reach the extended position, tongue 36 of 55 catch 34 will abut behind the strap 27 adjacent which it is attached and lock the strap 27 against movement, thus holding the entire train against movement and hence lock all the legs in extended position.

60 Now when the operator desires to fold the legs to put the table away, the operator lifts the finger catch or lip 37 away from bar 13, which will then permit strap 27 to slide by it and by folding any one leg, the other legs will 65 be folded simultaneously by the train of

straps and links. It will be noted also that practically all the parts including the various elements of the train, can be made of sheet metal, and that the construction is a very simple one and provides a durable and rigid table which may be manufactured and assembled at relatively low cost.

Having thus set forth the nature of the invention, what is claimed is:

1. In a table, a plurality of supporting legs pivoted to the table on individual pivots and each capable of folding against the under side of the table, and a movable connection connected to each of the legs and capable of transmitting movement from any leg to each of the other legs to extend the legs to supporting position and to fold them against the table, said connection including rigid straps, pivotally connected links connecting said straps to each other, and slotted guideways by which said straps are guided in their movements.

2. In a table, a plurality of supporting legs pivoted to the table on individual pivots arranged so that all the legs fold in the same direction with respect to the periphery of the table and a slidably mounted rigid strap between each pair of legs, and link connections between the straps and the legs capable of transmitting similar movement from any leg to each of the other legs to extend the legs to supporting position or fold them against the table.

3. In a table, a plurality of supporting legs pivoted to the table and foldable against it, and linked rigid pivoted means connecting all the legs including a slidably mounted rigid member between each adjacent pair of legs, guided links connecting adjacent rigid members, and a pivoted link connecting each leg to one of said members so that operation of any leg on its pivot will impart similar movement to all the other legs.

4. In a table, a plurality of supporting legs pivoted to the table and foldable against it, linked rigid pivoted means for connecting the legs with each other so that movement of any leg will give similar movement to the other legs including a rigid slidably mounted member between each pair of legs and links for connecting said members to each other and to the legs, and locking means for holding said connecting means against movement when the legs are in supporting position.

5. In a table, a plurality of supporting legs pivoted to the table so as to fold against it, guides secured to the table, rigid strap members slidably retained by said guides, rigid means linking said strap members together and connections from said members to the respective legs to swing them on their pivots by movement of said linked members.

6. In a table, a plurality of supporting legs pivoted to the table so as to fold against it, guides secured to the table, rigid strap mem-

- bers slidably retained by said guides, rigid means linking said strap members together and a pivoted brace connection from each strap member to each leg so that movement 5 of any leg to or from folded or extended position transmits similar movements to all the other legs.
7. In a table, a plurality of supporting legs pivoted to the table so as to fold against it, a slotted guide secured to the table on each side of the table, linked rigid straps slidably retained by said guides, a brace pivoted to each strap adjacent each leg and having pivotal connection with the legs and pivoted links 10 linking said straps.
8. In a table, a plurality of supporting legs pivoted to the table so as to fold against it, a slotted guide secured to the table adjacent each side of the table, rigid straps slidably retained by said guide, another slotted guide secured to the table adjacent each leg, pivoted connected link members guided by said last mentioned guide and pivotally interconnecting said strap members, a brace pivoted to each strap and to each leg whereby movement of any one leg imparts similar movement to all the other legs.
9. In a substantially rectangular table, a supporting leg pivoted thereto adjacent each 20 corner and adapted to fold against the table, a slotted guide mounted at each side of the table, a rigid strap slidably retained by said guide, a slotted guide mounted on the table diagonally of each corner thereof, a pair of pivoted links having their pivoting pin guided by said diagonal guide, the other ends of each of said pivoted links being each pivotally connected to one end of each of said rigid straps and a brace pivoted to each strap 25 and to each leg, whereby movement of any one leg imparts corresponding movement to each of the other legs.
10. In a substantially rectangular table, a supporting leg pivoted thereto adjacent each 30 corner and adapted to fold against the table, a slotted guide mounted at each side of the table, a rigid strap slidably retained by said guide, a slotted guide mounted on the table diagonally of each corner thereof, a pair of pivoted links having their pivoting pin guided by said diagonal guide, the other ends of each of said pivoted links being each pivotally connected to one end of each of said rigid straps and a brace pivoted to each strap 35 and to each leg, whereby movement of any one leg imparts corresponding movement to each of the other legs.
11. In a table, a plurality of supporting legs pivoted to the table so as to fold against it, a guide on each side of the table, linked rigid straps slidably retained by said guides, 40 a brace pivoted to each strap adjacent each strap and having pivotal connection with the legs, and pivoted links linking said straps.
12. In a table, a plurality of supporting legs pivoted to the table so as to fold against it, a guide carried by the table adjacent each side thereof, rigid straps slidably retained by said guides, another guide carried by the table adjacent each leg, pivoted connected link members guided by said last mentioned guide and pivotally connecting the strap members, and a brace pivoted to each strap and to each leg whereby movement of any one leg imparts similar movement to all the other legs.
13. In a substantially rectangular table, a supporting leg pivoted thereto adjacent each corner and adapted to fold against the table, a guide at each side of the table, a rigid strap slidably retained by said guide, a guide mounted on the table diagonally of each corner thereof, a pair of pivoted links guided by said diagonal guide adjacent their pivotal connection, the other ends of each of said pivoted links being pivotally connected to one of said rigid straps, and a brace pivoted to each strap and to each leg, whereby movement of any one leg imparts corresponding movement to each of the other legs.
14. In a substantially rectangular table, a supporting leg pivoted thereto adjacent each corner and adapted to fold against the table, a guide at each side of the table, a rigid strap slidably retained by said guide, a guide mounted on the table diagonally of each corner thereof, a pair of pivoted links guided adjacent their pivotal connection by said diagonal guide, the other ends of each of said pivoted links being each pivotally connected to one of each of said rigid straps, a brace pivoted to each strap and each leg whereby movement of any one leg imparts corresponding movement to each of the other legs, and manually releasable means locking one of said straps against movement when the legs are in supporting position whereby to hold all the legs in rigid supporting position.
- In testimony whereof I affix my signature.
JOHN KOVATS.
